US0D1061130S

(12) **United States Design Patent** (10) **Patent No.:** **US D1,061,130 S**
(45) **Date of Patent:** **** Feb. 11, 2025**

(54) **ELECTRIC GRINDER**

(71) Applicant: **NINGBO CHEFSHERE KITCHEN TECHNOLOGY CO., LTD.**, Ningbo (CN)

(72) Inventor: **Chao Zhang**, Ningbo (CN)

(**) Term: **15 Years**

(21) Appl. No.: **35/519,575**

(22) Filed: **Oct. 24, 2023**

(80) **Hague Agreement Data**

Int. Filing Date: **Oct. 24, 2023**

Int. Reg. No.: **DM/234082**

Int. Reg. Date: **Oct. 24, 2023**

Int. Reg. Pub. Date: **Dec. 29, 2023**

(30) **Foreign Application Priority Data**

Apr. 24, 2023 (CN) 202330230994.6

(51) **LOC (15) Cl.** **31-00**

(52) **U.S. Cl.**

USPC **D7/372**

Primary Examiner — Catherine S Posthauer

Assistant Examiner — Yen Le Southwood

(57) **CLAIM**

The ornamental design for an electric grinder as shown and described.

DESCRIPTION

1. Electric grinder

1.1 : Perspective

1.2 : Front

1.3 : Back

1.4 : Top

1.5 : Bottom

1.6 : Left

1.7 : Right

1.8 : State of use with a dust cover

1.9 : State of use without a dust cover

A grinding appliance used to grind objects into fine particles

or powders.

(Continued)

The broken lines showing portions of the electric grinder and environment form no part of the claimed design.

1 Claim, 9 Drawing Sheets
